GRANT HAMMOND, OF HARTFORD, CONNECTICUT, ASSIGNOR TO DALTON ARMS CORPORATION, OF NEW YORK, N. Y., A CORPORATION OF NEW YORK.

LOCK MECHANISM FOR FIREARMS.

1,184,950.

Specification of Letters Patent.

Patented May 30, 1916.

Application filed July 21, 1915. Serial No. 41,113.

To all whom it may concern:

Be it known that I, GRANT HAMMOND, a citizen of the United States, and a resident of Hartford, in the county of Hartford 5 and State of Connecticut, have invented a new and Improved Lock Mechanism for Firearms, of which the following is a specification.

My invention relates to the mechanism 10 for controlling the operation of the firing pin in firearms, and an object of my invention, among others, is to provide mechanism for this purpose that shall be cheap in construction, efficient in operation, and little 15 liable to be injuriously affected by dust, smoke, or other impurities.

A form of firearm embodying my invention and in the construction and use of which the objects herein set out, as well 20 as others, may be attained, is illustrated in the accompanying drawings, in which—

Figure 1 is the side view of a portion of a firearm embodying my invention, with parts broken away to show the construction. 25 Fig. 2 is a detail view in cross section through the firearm on plane denoted by dotted line 2—2 in Fig. 1.

My invention is not limited to use in a firearm of any special construction, but as 30 it readily adapts itself to that type that is held by a person and discharged from the shoulder, such type has been selected by me for the purpose of illustration herein.

In the accompanying drawings the number 35 10 denotes a stock and 11 the fore end of my improved firearm, which parts are preferably constructed of wood in a manner common to devices of this kind, and which parts are properly chambered and 40 recessed to receive the metallic members of the structure, which, in the present instance, include a receiver 12, a trigger plate 13 secured to the receiver by screws 15 and a barrel 14 secured to the receiver in any suitable 45 manner. A breech-bolt 16 is mounted for reciprocating movement in a breech-bolt chamber in the receiver, and a firing pin 17 extending into the breech-bolt has a head 18 secured thereto and projecting beyond the end thereof. As the construction 50 of the parts above referred to will be readily understood, further and detailed description is omitted herein.

A breech-bolt sleeve 19 is secured to the 55 rear end of the breech-bolt as by means of

screw threads, this sleeve having a threaded recess 20 to receive the end of said bolt, the latter being rotatable to a limited extent within this recess. A recess 21 for the reception of the neck of the head of the firing pin extends inwardly from the rear end of the breech-bolt sleeve, the inner end of said neck resting against the bottom of this recess, and a firing pin opening 22 extends between the recesses 20 and 21, a slot 23 60 through the bottom of the breech-bolt sleeve at this end also cutting into these recesses. A breech-bolt actuating handle 24 is secured to the breech-bolt in any suitable manner.

A neck 25 projects from the firing pin 70 head and a cocking prong 26 is located in the slot 23 in the breech-bolt sleeve, the cocking prong being provided with a cocking shoulder 27 located in position to be engaged by a sear 28 mounted and located in 75 a slot extending through the bottom of the receiver at its rear end. A trigger is slotted at its upper end, within which slot the sear 28 is located, a pivot pin 30 extending through the side parts of the trigger thus 80 formed and pivotally connecting it to the sear. These side parts of the trigger are provided with an initial bearing 31 and a disengaging bearing 32, the former being located nearest the pivot 30, first engaging 85 the frame and serving to impart initial movement to the sear with a certain amount of power transmitted from the trigger, and the latter engaging the frame just before the sear becomes disengaged from the shoulder 27, acting at the time of disengagement of the sear from said shoulder and requiring a little more power to be applied from the trigger than at the initial movement of the sear. This multiple fulcrum enables the 90 greatest amount of power to be applied at the time of initial movement of the sear, and up to nearly the point of disengagement of the sear from the firing pin, and at the time of disengagement of said parts, and 95 when less power is required to disengage them the second fulcrum is brought into action. This multiple fulcrum enables the operator to know when the point of disengagement of the sear and firing pin has 100 been nearly reached by apprising him through the "feeling" of the trigger when the second fulcrum comes into action.

A presser 33 is seated in a well extending 105 downwardly from the upper edge of the 110

trigger between the side parts 34, this presser being seated upon a spring 35 and acting to retain the trigger 29 with its lower end in its forward position. The construction herein shown and described may be changed to a greater or lesser extent and yet be within the spirit and intent of the invention.

I claim—

- 10 1. A firing mechanism for a firearm including a receiver, a sear pivotally mounted in said receiver, a trigger pivotally mounted on the sear and having a part to engage said receiver, and a spring pressed member located in one of said parts and pressing against the opposite part to force both of said members to their positions of rest.
- 15 2. A firing mechanism for a firearm including a receiver, a sear pivotally mounted in said receiver, a trigger pivotally mounted on the sear and having a part to engage said receiver, and a spring pressed member located in the trigger and pressing against the sear to force both the trigger and sear 25 to their positions of rest.
- 20 3. A firing mechanism for a firearm including a receiver having a slot extending through its bottom wall, a breech-bolt mounted in the receiver, a sear pivotally

mounted in said slot, a trigger pivotally attached to said sear, and a spring pressed member located between the trigger and sear to force the sear toward the breech-bolt and to force the trigger.

4. A firing mechanism for a firearm including a receiver having a slot through its bottom wall, a breech-bolt mounted in the receiver, a sear pivotally mounted in said slot, a trigger having a forked end within which said sear is received, said trigger being pivotally attached to the sear, and a spring actuated presser mounted in the trigger and thrusting against said sear to retain the trigger and sear in their positions of rest.

5. A firing mechanism for a firearm including a receiver, a sear pivotally mounted in said receiver, a trigger having a grooved end within which said sear is received, a well extending inwardly from the bottom of said groove, a pivot uniting the sear and trigger, a presser mounted in said well, and a spring underlying the presser.
